(57) **CLAIM**

The ornamental design for a vein authentication sensor, as shown and described.

DESCRIPTION

FIG. 1 is a perspective view of front, bottom and left side of a vein authentication sensor showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof showing an intermediate state that a USB connector is rotated by 90 degrees;

FIG. 9 is a perspective view thereof showing a state that a USB connector is rotated by 90 degrees;

FIG. 10 is a front view thereof showing a state that a USB connector is rotated by 90 degrees;

FIG. 11 is a rear view thereof showing a state that a USB connector is rotated by 90 degrees;

FIG. 12 is a left side view thereof showing a state that a USB connector is rotated by 90 degrees;

FIG. 13 is a right side view thereof showing a state that a USB connector is rotated by 90 degrees;

FIG. 14 is a top view thereof showing a state that a USB connector is rotated by 90 degrees;

FIG. 15 is a bottom view thereof showing a state that a USB connector is rotated by 90 degrees;

FIG. 16 is a perspective view thereof showing an intermediate state that a USB connector is rotated by 180 degrees;

FIG. 17 is a perspective view thereof showing a state that a USB connector is rotated by 180 degrees;

FIG. 18 is a front view thereof showing a state that a USB connector is rotated by 180 degrees;

FIG. 19 is a rear view thereof showing a state that a USB connector is rotated by 180 degrees;

FIG. 20 is a left side view thereof showing a state that a USB connector is rotated by 180 degrees;

FIG. 21 is a right side view thereof showing a state that a USB connector is rotated by 180 degrees;

FIG. 22 is a top view thereof showing a state that a USB connector is rotated by 180 degrees;

FIG. 23 is a bottom view thereof showing a state that a USB connector is rotated by 180 degrees; and,

FIG. 24 is a reference view of usage.

The broken lines shown are included for the purpose of illustrating the unclaimed portions of a vein authentication sensor and form no part of the claimed design.
